UNITED STATES PATENT OFFICE.

NOAH N. NEHER, OF LOS ANGELES, CALIFORNIA.

MANIFOLD CUT-OFF FOR INTERNAL-COMBUSTION ENGINES.

Application filed June 9, 1926. Serial No. 114,638.

This invention relates to a device for controlling the supply of fuel to an internal combustion engine and particularly to a device adapted to be mounted upon the intake manifold of the engine. The device has been primarily designed to be used in conjunction with the construction disclosed in my co-pending application, Serial No. 114,637 filed June 9, 1926, but it may be 10 equally well employed with other constructions.

An object of this invention is to provide a manifold cut-off for opening and closing the entrance to the manifold from the internal combustion engine, the improved cut-off being of simple and durable construction and being capable of being easily and quickly operated.

Another object of this invention is to 20 provide an improved cut-off for intake manifolds on internal combustion engines which will serve as a lock for the engine, it being understood that the improved device is readily adapted to be used on internal combustion engines on automobiles.

A further object of this invention is to 30 provide a cut-off adapted to serve as a lock for the manifold of an internal combustion engine, which is substantially theft proof in that in the event of the operating mechanism being broken or cut by a potential thief in an attempt to open the lock, the cut-off is very likely to remain closed unless the potential thief should be extremely careful.

35 With the foregoing and other objects in view which will be made manifest in the following detailed description and specifically pointed out in the appended claims, reference is had to the accompanying drawings for an 40 illustrative embodiment of the invention, wherein:

Figure 1 is a plan view of one form of construction, the cover being shown as having been removed and the cut-off shown in 45 closed position.

Fig. 2 is a view similar to Fig. 1 with the cut-off shown in open position.

Fig. 3 is a vertical section taken substantially on the line 3-3 of Fig. 2,

50 Fig. 4 is a view similar to Fig. 1, illustrating a modified form of construction, and

Fig. 5 is a view similar to Fig. 4 showing the cut-off in open position.

Referring to the accompanying drawings 55 wherein similar reference characters designate similar parts throughout, the improved

cut-off consists of two plates 10 and 11 which are spaced by a third plate 12. The three plates are bolted together as by bolts or rivets 14, and the housing thus formed is 60 adapted to be inserted between the companion flanges 15 and 16 which are usually provided upon the conventional intake manifold and carburetor on an internal combustion engine. The three plates are preferably provided with apertures 17 to receive bolts passing through the flanges. In the central plate 12 there is formed an elongated aperture 18, and adjacent one end of each of the plates 10 and 11 there is formed an 70 aperture 19 or 20, registering with each other and which are adapted to register with the interior of the manifold. A disc-like closure 21 fits within the aperture 18 and is slidable between the plates 10 and 75 11. This disc-like closure is capable of closing the passage provided through the housing by the apertures 19 and 20, or if swung into the position shown in Fig. 2 the passage of fuel through the manifold will be permitted. In the central plate 12 adjacent the 80 side of the aperture 18 there is formed a circular notch 22 which receives a circular projection 23 formed on a lever 24. The lever 24 is thus pivotally mounted within 85 the housing and it is provided with two arms, the arm 25 being pivotally connected to the disc-like closure 21 as indicated at 26. The other arm of the lever 24, which is indicated at 27, cooperates with the first 90 arm 25 to form a notch 28 which receives the arm 29 of a second lever generally indicated at 30. The second lever has a circular projection 31 fitting within a recess 32 formed in the central plate 12 on the opposite side of the aperture 18 from the 95 recess 22. In this manner the second lever 30 is pivotally mounted within the casing. In addition to the arm 29 this second lever has an arm 33 which cooperates with the first arm 29 to form a notch 34. The notch 34 receives an arm 35 on a third lever generally indicated at 36, which is pivotally connected to the housing as indicated at 37 by a construction similar to that which 100 is employed for pivotally fastening the other levers in the housing. In the third lever 36 there is formed a notch 38 preferably circular in form, and an actuating or operating wire 39 extends into the housing 105 through the aperture or opening 40 formed in the plate 12. This wire has its end bent 110

into a circle which fits within the notch 38. The wire on the outside of the housing is enclosed by a flexible hose 41 preferably formed of steel wire. It is adapted to be 5 operated from the dashboard of a vehicle to which the device is applied by means of a lock, and when used in conjunction with the construction shown in my co-pending application, it is operated by the lock controlled ignition switch. Adjacent the notch 32 a semi-circular groove 42 is formed in the plate 12 and a coil spring 43 fits within this groove having one end bearing against the side of the aperture 18 and the other bearing 15 against the arm 33 on the second lever 30.

The operation of the device is as follows: When the operating or actuating wire 39 is pulled, the third lever will be swung causing its end to engage the arm 33 on the second lever, thus swinging the second lever. The arm 29 on the second lever engages the arm 27 on the first lever, swinging the first lever and causing the closure 21 to uncover the apertures 19 and 20. This movement is done 20 against the action of the coil spring 43, and upon release of the wire 39 or upon its being pushed forwardly, the coil spring will serve to return the levers and closure from the 25 position shown in Fig. 2 to the position shown in Fig. 1.

A feature of the construction is as follows: It will be readily understood that the improved manifold cut-off is designed to prevent unauthorized operation of the engine. 35 It is readily appreciated that a potential thief might cut the hose 41. To take care of such a contingency attention is directed particularly to the shape of the lever 36 and the arm 33 on the second lever 30. If the 40 hose should be cut, a thief on pulling the wire 39 would be very likely to pull this wire too far, and in such event the end of the lever 36 rides over the small projection formed on the arm 33 and when this is done, 45 the third lever 36 no longer controls the second lever. Consequently, the coil spring 43 is immediately free to throw the second and first levers and the closure 21 back into closing position, so that the manifold remains 50 cut off. If a thief should attempt to push the wire 39 to cause the lever 35 to again engage the lever 30, it will be readily understood from an inspection of Fig. 1 that the 55 end of the arm 33 is in such position that the lever 36 cannot pass by it. Consequently, even if a thief should cut the hose and pull upon the wire 39, he is very likely to pull it 60 too far, causing the lever 36 to disengage the lever 30, and when these levers have once been disengaged, they cannot subsequently be caused to engage by movement of the wire 39. The engine therefore remains locked, so 65 that it cannot be operated, and can only be again operated after the complete cut-off has been taken off of the manifold, the plates 10

and 11 separated and the lever 36 lifted over the arm 33, so as to enter the notch 34.

The modification shown in Figs. 4 and 5 is very similar to the modification shown in Figs. 1 and 2, the main difference being that in Figs. 1 and 2 the hose 41 is connected to the end of the housing, whereas in Figs. 4 and 5 the hose is connected to the side of the housing. Furthermore, the shape of the lever 36^a corresponding to the lever 36 is slightly changed to provide for the attachment of the actuating wire. In all other respects the modification shown in Figs. 4 and 5 is the same as that shown in Figs. 1 and 2, and it will be readily understood that in the event that the operating wire shown in Figs. 4 and 5 should be pulled too far, the lever 36^a will disengage the lever 30^a and cannot be caused to again engage it by the wire.

From the above described construction it 85 will be readily appreciated that an improved manifold cut-off or a device for controlling the supply of fuel to an internal combustion engine is provided which will easily and quickly open or close the conduit conveying 90 fuel to the engine. Furthermore, upon attempted operation by cutting the hose 41 it will be readily understood that the lock cannot be opened and caused to remain open unless the wire 39 is pulled just so far and no 95 farther. This feature, because of the fact that it is very difficult to determine what would be the limit that the wire 39 can be pulled without causing the lever 36 to disengage the arm 33, enables the device to be 100 effectively employed as an automobile lock.

It will be understood that various changes in the detail of construction may be made without departing from the spirit and scope of the invention as defined by the appended 105 claims.

I claim:

1. A device for controlling the supply of fuel to an internal combustion engine comprising a valve adapted to be inserted in the fuel conduit leading to the engine, an actuating member, and means connecting said actuating member to the valve whereby the valve may be opened and closed by the actuating member, said means being so constructed that if the actuating member is moved to a position beyond the full open position of the valve, the valve will automatically return to its closed position.

2. A device for controlling the supply of fuel to an internal combustion engine comprising a valve adapted to be inserted in the fuel conduit leading to the engine, an actuating member, and means connecting said actuating member to the valve whereby the valve may be opened and closed by the actuating member, said means being so constructed that if the actuating member is moved to a position beyond the full open position of the valve, the valve will automatically 120 125 130

cally return to its closed position and the actuating member will no longer be capable of actuating the valve.

3. A device for controlling the supply of fuel to an internal combustion engine comprising a valve adapted to be mounted in the fuel conduit leading to the engine, an actuating wire, a hose enclosing the wire, and means connecting the wire to the valve whereby the wire upon being moved between two predetermined positions may move the valve from open to closed position or vice versa, but upon moving the wire beyond one of the predetermined positions, it will be no longer connected to the valve so as to be incapable of actuating it.

4. A device for controlling the supply of fuel to an internal combustion engine comprising a valve adapted to be mounted in the fuel conduit leading to the engine, an actuating wire, a hose enclosing the wire, and means connecting the wire to the valve whereby the wire upon being moved between two predetermined positions may move the valve from open to closed position or vice versa, but upon moving the wire beyond the predetermined position wherein the valve is open, the valve will automatically be returned to its closed position and remain closed regardless of further movements of the wire.

5. A device for controlling the supply of fuel to an internal combustion engine comprising a housing adapted to be mounted in a fuel conduit leading to an internal combustion engine, said housing having an aperture therein through which the fuel may pass, a valve closure in the housing adapted to open and close the aperture, an angular lever in the housing, means connecting one arm of the lever to the valve closure, a second lever pivoted upon the housing having an arm engageable upon the second arm of the first lever, and means for actuating said second lever to cause the first lever to move the valve closure.

6. A device for controlling the supply of fuel to an internal combustion engine comprising a housing adapted to be mounted in a fuel conduit leading to an internal combustion engine, said housing having an aperture therein through which the fuel may pass, a valve closure in the housing adapted to open and close the aperture, an angular lever in the housing, means connecting one arm of the lever to the valve closure, a second lever pivoted upon the housing having an arm engageable upon the second arm of

the first lever, and a spring associated with the first lever urging it to move the valve into closed position, said levers being so arranged that if the second lever is moved beyond a position wherein the valve is fully open, it will disengage the first lever, allowing the spring to return the first lever and closure into closed position, in which the second lever may no longer be caused to operatively engage the first lever.

7. A device for controlling the supply of fuel to an internal combustion engine comprising a housing adapted to be inserted in the fuel conduit leading to the engine, there being an aperture in said housing, a valve closure adapted to close the aperture, a first lever pivoted in the housing having two arms one of which is pivotally connected to said closure, a second lever pivoted in the housing having two arms, one of which engages the other arm of the first lever, spring means associated with the second lever urging it into that position in which the closure is in closing position, a third lever pivoted in the housing having an arm engageable upon the other arm of the second lever, and means for moving said third lever to cause it to actuate the first and second levers and thus move said closure into open position.

8. A device for controlling the supply of fuel to an internal combustion engine comprising a housing adapted to be inserted in the fuel conduit leading to the engine, there being an aperture in said housing, a valve closure adapted to close the aperture, a first lever pivoted in the housing having two arms one of which is pivotally connected to said closure, a second lever pivoted in the housing having two arms, one of which engages the other arm of the first lever, spring means associated with the second lever urging it into that position in which the closure is in closing position, a third lever pivoted in the housing having an arm engageable upon the other arm of the second lever, and means for moving said third lever to cause it to actuate the first and second levers and thus move said closure into open position, said third lever and said other arm on the second lever being so arranged that if the third lever is moved beyond the position in which the closure is in fully open position it will disengage the second lever and be incapable of again operatively engaging it.

In testimony whereof I have signed my name to this specification.

N. N. NEHER.
